UNITED STATES PATENT OFFICE.

EVA HEETER BIXLER, OF NORTH MANCHESTER, INDIANA.

INDICATOR.

1,125,447.

Specification of Letters Patent.

Patented Jan. 19, 1915.

Application filed September 29, 1913. Serial No. 792,441.

To all whom it may concern:

Be it known that I, EVA H. BIXLER, a citizen of the United States, residing at North Manchester, in the county of Wabash and State of Indiana, have invented certain new and useful Improvements in Indicators, of which the following is a specification, reference being had to the accompanying drawings.

- 10 This invention relates to new and useful improvements in protectors or indicators and more particularly to an indicator adapted for application to bottles and similar receptacles containing poison, the object of 15 the invention being to provide an indicator, which when applied to the neck of a bottle will inclose the cork and at the same time warn the person removing the cork that the bottle contains poison.
- 20 A further object of the invention is the provision of an indicator of the above character which is preferably in the form of a metal cap constructed of a single sheet of metal bent to inclose the cork and which 25 can be quickly and readily applied to the neck of the bottle or removed therefrom and when applied is resiliently held into engagement with the bottle neck.

Another object of the invention is the 30 provision of a device of this character which will possess advantages in points of efficiency and durability, is inexpensive of manufacture and at the same time is simple in construction and operation.

35 With the above and other objects in view, this invention consists in the novel features of construction and the combination of and arrangement of parts to be hereinafter more fully described, pointed out in the claim 40 and shown in the accompanying drawings, in which—

Figure 1 is a side elevation illustrating my improved indicator applied to the neck of a bottle; Fig. 2 is a plan view of the 45 blank from which the indicator is formed, the same being shown in dotted lines, as in a folded position.

In carrying out my invention, I provide a blank of sheet metal and in the construction of my improved indicator I form a body plate 1 and extending outwardly in opposite directions and radially arranged are the arms or tabs 2, the ends of each of the alined tabs being curved or coiled upon 50 themselves to form sleeves. In the blank, as shown in Fig. 2, the ends of two of the

5 tabs are merely bent inwardly upon themselves to form the sleeves 3 while the tabs which are disposed at right angles to these first mentioned tabs are provided at their outer ends with the angular bent portions 4, thence coiled upon themselves, as shown at 5, to form a sleeve which is adapted to receive a coil spring 6 and is further adapted to be resiliently engaged beneath the 60 head of the bottle 7 so as to removably retain the indicator in position.

As indicated in Fig. 1, it will be readily apparent that my improved protector or indicator is applied to the neck of the bottle, 70 the ends of two of the alined ends of the tabs 2 are merely coiled upon themselves and engaged beneath the head 7 of the bottle neck, the central portion 1 of the body fitting tightly against the outer end of the 75 cork so as to retain the same in position. The indicators are further held in position by means of the alined tabs 2', the outer ends of which are provided with the angular bent portions 4', thence bent upon 80 themselves to form the sleeve 5' which is adapted to engage beneath the head 7 of the bottle neck so as to resiliently retain the indicator in position.

The coil spring 6 is provided and is 85 adapted to be arranged within the sleeves 5 and 5' so as to resiliently retain the same in engagement with the head 7 of the body.

From the above description taken in connection with the accompanying drawings, 90 it will be readily apparent that I have provided a simple and durable indicator which can be quickly and readily applied to the neck of a bottle and adapted to inclose a cork so as to warn the person removing the 95 cork that the contents of the bottle is poison. It will also be apparent that by having the protector or indicator constructed of a single piece of sheet metal, it may be manufactured and placed on the market at a very 100 small cost.

While I have shown and described the preferred form of my invention it will be obvious that various changes in the details of construction and in the proportions may 105 be resorted to for successfully carrying my invention into practice without sacrificing any of the novel features or departing from the scope of the appended claim.

What I claim is:—

The combination with a bottle neck and its head portion, of a cap including a rec-

tangular body portion, arms formed integral with the side portions of said cap and arranged in opposed relation, said arms being tapered toward their outer ends and adapted to be disposed at right angles to the body, certain of said arms having their outer ends bent inwardly upon a horizontal plane and adapted to be engaged beneath the head of the bottle neck, and their extreme ends bent outwardly upon themselves to form sleeves, the other of said arms having their outer ends bent upon themselves

to form sleeves arranged at right angles to the first mentioned sleeves, and a coil spring arranged within said sleeves to resiliently retain the same beneath the head portion of the bottle neck. 15

In testimony whereof I hereunto affix my signature in the presence of two witnesses.

EVA HEETER BIXLER.
